UNITED STATES PATENT OFFICE

2,480,030

TOY HOUSING

Edward C. Karwacki, Chicago, Ill.

Application February 4, 1946, Serial No. 645,407

3 Claims. (Cl. 46—12)

1

The present invention relates to toy housings and has for its principal object the provision of a housing with means therein provided for ejecting missiles such as toy vehicles, balls, etc.

A still further object of the present invention is the provision of a housing of the character above indicated having a slideable door, with means for opening said door and simultaneously actuating the ejecting mechanism to propel the missile from the housing and through the open door.

A still further object of the present invention is the provision in a housing of the character above indicated of a rod, simulating a chimney pipe, which, when depressed actuates the mechanism for opening the door in the housing and simultaneously actuates the mechanism for ejecting a missile from the housing through the open door.

With the above general objects in view and others that will appear as the invention is better understood, the same consists in the novel construction, combination and arrangement of parts hereinafter more fully described, illustrated in the accompanying drawing and pointed out in the appended claims.

In the drawings forming a part of this application and in which like designating characters refer to corresponding parts throughout the several views;

Fig. 1 is a front elevational view of the housing;

Fig. 2 is a transverse cross-sectional view therethrough on a vertical plane;

Fig. 3 is a cross-sectional view, substantially on line 3—3 of Fig. 2, showing the door closed and the missile ejecting mechanism conditioned for use; and

Fig. 4 is a similar view with door open, with the missile ejecting mechanism in the position immediately after its operation.

Referring in detail to the present drawings there is shown therein a housing including floor 10, a pair of spaced side walls 11, front wall 12, rear wall 13, and roof 14 supported by said walls 11, 12 and 13. Rigidly supported upon said roof 14 is an oblong, rectangular block 15 which simulates a chimney.

Centrally of front wall 12, and adjacent floor 10 a rectangular door opening 16 is provided. A door panel 17 is positioned rearwardly of said opening 16 for vertical sliding movement upon the inner face of said front wall 12, and is guided in its vertical sliding movement by a pair of guiding rails 18 rigidly affixed to the inner face of said front wall 12, and adjacent the vertical sides of door opening 16. Said guiding rails 18 are provided with a plurality of opposed lips 19

spaced from said wall 12 for preventing door 17 from disengagement with said front wall 12.

Extending through chimney 15, and in an axial longitudinal relation therewith, is a cylindrical rod 20, the upper end of which normally extends above the upper end of said block 15, and simulates a chimney pipe. Said rod 20 is in the proximity of said rear wall 13, and for preventing lateral movement of said rod 20, the lower end thereof is passed through and guided within loop 21 of pin 22 driven into and rigidly supported by said rear wall 13.

Supported upon pivot 23, driven into rear wall 13, and adjacent one side wall 11, is arm 24, its free end terminating adjacent the opposite side wall 11. Said arm 24 is in a spaced parallel relation with rear wall 13, the same being disposed between said rear wall 13 and said rod 20. Driven into said arm 24 and adjacent said rod 20 is staple 25, within which pin 26, carried by rod 20, enters, and through the medium of said staple 25 and pin 26 said arm 24 may be angularly shifted in an upright direction, when said rod 20 is shifted.

Passed through opening 27, made in the free end of said arm 24, and tied thereto is cord 28. Said cord 28 is extended through staple 29, which is affixed to said rear wall 13 and through a similar staple 30, the latter driven into said front wall 12. Both said staples 29 and 30 are in proximity of roof 14, so that considerable portion of said cord 28 remains below said roof 14 and disposed between said walls 12 and 13. The opposite end of said cord 28 is affixed to the upper end of door 17, and centrally thereof, as at 31.

Affixed to said rear wall 13, and forwardly extending therefrom, and below roof 14, is a rectangular block 32, to the outer, free end of which an oblong, narrow and resilient spring 33 is affixed by means of screw or nail 34. The lower free end of said spring 33 extends towards floor 10, and is adapted for engagement by a metallic, resilient hook 35, the shank of which rests upon the face of rear wall 13 and is there engaged and retained by heads of a pair of spaced screws or nails 36, by virtue of which arrangement the shank of said hook 35 may be longitudinally adjusted so as to be in a proper extended position for engaging the lower end of spring 33, as is seen in Figs. 2 and 3.

The lower end of rod 20 carries a horizontal and laterally extending bar 37, which is in a parallel relation with rear wall 13 and disposed above said hook 35, but on a plane between the shank and the engaging free end thereof.

Floor 10 is provided with a pair of spaced rails 38 within which toy vehicle 39 or other missile may be positioned for ejection from the housing. Said rails 38 are in alignment with door opening 16 so as to prevent the missile from striking

ing front wall 12 during its ejection from the housing.

Assuming that door 17 is in a closed position relative to the door opening 16, with spring 33 in engagement with hook 35, with vehicle 39 within rails 38, as shown in Figs. 2 and 3, rod 20 remains in a raised position, with bar 37 in an elevated position above said hook 35. In that position arm 24 also remains in a raised position, as is indicated by full lines in Fig. 2. Exerting manual pressure upon the outer end of rod 20, which extends above chimney 15, rod 20 is caused to shift downwardly, thereby shifting arm 24 downwardly to the position indicated by dotted lines in Fig. 2. The shifting of said arm 24 is accomplished through the medium of pin 26, as it bears upon staple 25. The downward shifting of arm 24 pulls cord 28, at the end thereof which is tied to arm 24 causing said cord 28 to shift downwardly with said arm 24, thereby pulling the opposite end of said cord 28 upwardly, and thereby shifting door 17 upwardly and out of opening 16. The operation of door shifting mechanism aforesaid is timed with the operation of bar 37, so that when door 17 is completely out of opening 16, at that very instant bar 37 comes in contact with hook 35, depressing the same downwardly for disengaging its operative outer end from spring 33. The disengaged spring 33 with an operatively strong force hits the rear end of vehicle 39 and propels the same out of the housing through opening 16.

It is observed that door 17 is of sufficient weight, so that when manual pressure upon rod 20 is released, door 17 due to its gravity shifts downwardly within guiding rails 18 for closing opening 16. The gravitational force of downwardly sliding door 17 exerts pulling action upon cord 28 in the opposite direction from that hereinabove described, thereby shifting arm 24 upwardly and through staple 25 and its engagement with pin 26 shifts rod 20 upwardly to its inoperative position, and thereby shifting bar 37 out of engagement with hook 35.

Before however manual pressure upon rod 20 is completely released, rod 20 is released to a slight degree so as to permit bar 37 to come out of engagement with hook 35. Thereupon vehicle 39 is replaced within track 38, and when the same is shifted toward rear wall 13 pressure thereby is exerted upon the lower end of spring 33 to spring the same into an engagement with hook 35, position shown in Fig. 3, and thereupon the manual hold upon rod 20 is completely released. This causes downward shifting of door 17, reconditioning the device for a repeated operation.

While there is described herein a preferred embodiment of the present invention, it is nevertheless to be understood that minor changes may be made therein without departing from the spirit and scope of the invention as claimed.

What I claim as new is:

1. In combination a toy garage including a plurality of side walls, one of said walls having an opening therein, a vertically sliding door in association with said opening, a slidable rod passing into said garage, an arm pivoted at one end to one of said walls for swinging movement, said arm having a free end, connecting means between said rod and arm for swinging the latter in one direction when said rod is manually shifted, said connecting means being positioned in closer proximity to the pivoted end of said arm than to the free end, a cord connecting said door with said rod for sliding said door upwardly when said rod

is manually shifted, the weight of the door as it slides downwardly being capable of reversely shifting said arm and said rod to normal positions, a resilient member within said housing positioned to propel a toy vehicle through said opening, a slidable catch for holding said resilient member in a biased position, and a bar carried upon said rod adapted to engage said catch as said door reaches an open position to release said resilient member.

2. In combination a toy garage including a plurality of side walls, one of said walls having a door opening therein, a roof supported on said side walls, a vertically sliding door in association with said opening, a vertically sliding rod passing through said roof into said garage, an arm pivoted at one end to one of said side walls for upright swinging movement, connecting means between said rod and arm for swinging the latter downwardly when said rod is manually shifted, a cord connecting said door with said arm for sliding said door upwardly when said rod is manually shifted, the weight of said door as it slides downwardly being capable of shifting said arm and rod to normal positions, a resilient member within said housing positioned to propel a toy vehicle through said opening, a slidable catch for holding said resilient member in a biased position, and means carried upon said rod adapted to engage said catch as said door reaches an open position to release said resilient member.

3. In combination a toy garage including a plurality of side walls, one of said side walls having a door opening therein, a roof supported on said side walls, a block mounted upon said roof simulating a chimney, a vertically sliding door in association with said opening, a slidable rod passing through said block and in a substantially longitudinal axial relation therewith, normally said rod extending above said block in simulation of a chimney pipe, an arm pivoted at one end to the side walls opposite said door opening for upright swinging movement, said arm having a free end, connecting means between said rod and arm for swinging the latter downwardly when said rod is manually shifted in a downward direction, said connecting means being positioned in closer proximity to the pivoted end of said arm than to the free end, a cord connecting said door with said rod for sliding said door upwardly when said rod is manually shifted in a downward direction, the weight of said door as it slides downwardly being capable of shifting said rod and arm upwardly to normal positions, a resilient member mounted on the side wall opposite said door opening positioned to propel a toy vehicle through said opening, a slidable catch mounted on the side wall opposite the door opening for holding said resilient member in a biased position, and a bar carried upon said rod adapted to engage said catch as said door reaches an open position to release said resilient member whereby the toy vehicle is propelled from the garage through the door opening.

EDWARD C. KARWACKI.
